UNITED STATES PATENT OFFICE

ARCHIE REXALD WOLFE, OF SUMMIT, NEW JERSEY

ELECTRIC SOCKET SWITCH

Application filed March 6, 1929. Serial No. 344,889.

(GRANTED UNDER THE ACT OF MARCH 3, 1883, AS AMENDED APRIL 30, 1928; 370 O. G. 757)

My invention relates to improvements in spring force make and break switches adapted to be used for electric light sockets and the like, and the objects of the improvements are, first, to provide in a standard electric light socket a new and improved type of spring force make and break switch of especial long durability, high efficiency and low cost manufacture, and to design said socket 5 to accommodate said switch; second, to produce an electric socket switch of low cost manufacture readily designed to be used in electric light sockets in general and for all electrical switching purposes requiring 10 spring action make and break of electric currents.

One form of my invention is illustrated in the accompanying drawing, in which, Fig. 1 is a view of the top of the socket from a point 15 vertically above its center; Fig. 2 is a vertical sectional view on the broken line 1—1, Fig. 1, showing the switch in the "on" position; Figure 2a is a similar view showing the switch in the "off" position; Fig. 3 is a view of the 20 bottom of the base of said socket showing the position of the center contact terminal post and shell terminal post; Fig. 4 is a view in perspective of one side of the lower section of the insulation body of said socket with all 25 parts of the socket removed except the center contact terminal post 33, the metal contact 31, and the threaded bolt 32, which electrically connects said terminal post and metal contact to each other and secures them to said 30 lower section; Fig. 5 is a view of a part of the invention showing the top of the reciprocating control rod of the switch with the spring cam removed therefrom; Fig. 6 is a view of the bottom center contact as removed 35 from said socket; and Fig. 7 is a perspective view of a part of the invention showing the fulcrum and power end of the triple ended contactor of said switch.

Similar numerals refer to similar parts 40 throughout the several views.

The threaded metal tie bolts 1, and 2, pass through apertures provided in and secure in place the screw shell 3, upper insulation body section 4, and lower insulation body section 5. The threaded nut 6, secures said bolt 1, 50 and is countersunk in the bottom of said lower section 5, and the shell post terminal post 7, is provided with a threaded aperture which serves as a securing nut for said bolt 2.

A portion of the center contact 8, passes 55 down through an aperture provided in section 4, and is then bent at right angles and secured to said section 4, by the rivet 9.

One end of the triple ended bridge member 10, is fulcrumed and hinged to said center 60 contact 8, by means of the tip 11, of said bridge member which projects through the aperture 12, of said center contact 8, and the shoulder 13, of said bridge member 10, bear on and make contact with said center 65 contact 8. The tip flange 15, of said bridge member 10, retains said tip 11, within said aperture 12, during the ordinary operating movement allowed said contactor 10, but the increased movement allowed the latter during 70 assembly and disassembly of said socket permits said tip 11, to be readily removed from or inserted in said aperture 12. The power end 16, of said bridge member 10, is engaged and its movement is controlled by 75 the spring cam 17, which is secured to the reciprocating control rod 18. The latter is provided with the insulation handles 19, and 20, which project on the outside of said section 5, and with the vertical stops 21, and 22, 80 which prevent undue elevation during operation of one end of said control rod 18, and the horizontal stops 23, and 24, see Figure 5, which project into the slots 25, and 26, respectively, see Figure 4, in said section 5, prevent undue elevation of the other end of said control rod 18. The bridge member 10 is guided in its reciprocal movement by 85 an insulated member 34 disposed within the cavity 27, as shown in Fig. 4.

Said bridge member 10, spring cam 17, and control rod 18, are accommodated in the switch cavity 27, in the upper end of said section 5, and the cavities 28, and 29, at each end of the bottom of said switch cavity 27, accommodate said handles 19, and 20, respectively, and serve to limit the reciprocating movement of said control rod 18.

10 In the on position of the switch as shown in Fig. 2, the contact end 30, of said bridge member 10, makes contact with the metal contact 31, which is countersunk into the upper end of said section 5, projects over said switch cavity 27, and is secured in place by the metal bolt 32, which passes through an aperture provided in said section 5, and is secured by machine thread to the center contact terminal post 33, of said socket.

15 The circuit of the above switch is through the binding post 33 for the center contact, bolt 32, metal contact 31, bridge member 10, center contact 8, device in shell, bolt 2, and shell binding post 7.

20 The invention described herein may be manufactured and used by or for the Government of the United States for governmental purposes without the payment to me of any royalty thereon.

25 I claim:

30 1. In an electric socket comprising a shell, center contact, center contact terminal post and shell terminal post, a bridge member hinged to said center contact, a longitudinally movable spring cam for actuating said bridge member, a means on the outside of said socket for operating said spring cam, a metal contact engageable with said bridge member, and a permanent electrical connection between said metal contact and center contact terminal post.

35 2. In an electric socket comprising a shell, center contact, center contact terminal post and shell terminal post secured to an insulation body, a triple ended bridge member with its fulcrum end hinged to said center contact, a spring cam secured to a control rod and engaging the power end of said bridge member for actuating the latter, a metal contact electrically connected to said center contact terminal post for engaging the contact end of said bridge member during the on position of the latter, and a means on the outside of said insulation body for reciprocating said control rod.

40 3. In an electric socket and the like comprising an insulation body supporting the two switching contacts of an electric circuit, a switch comprising a triple ended bridge member with one end hinged to one of said switching contacts, a longitudinally movable spring cam supported by said insulation body and acting on and engaging the second end of said bridge member for moving the third end into or out of contact with the other of said circuit switching contacts, and

means on the outside of said insulation body for operating said spring cam.

4. In an electric socket, a switch including a plurality of switching contacts, a triple ended bridge member hingedly connected to one of said contacts by one of its ends, a longitudinally movable spring cam engaging with another of the ends to cause the third end to engage with or disengage from the other of said contacts, and means for operating said spring cam.
